UNITED STATES PATENT OFFICE.

LUCIEN ANDUZE, OF LIMOGES, FRANCE.

DESIGN FOR A COVERED DISH OR SIMILAR ARTICLE.

Application filed April 7, 1926. Serial No. 17,201. Term of patent 14 years.

To all whom it may concern:

Be it known that I, LUCIEN ANDUZE, a citizen of the Republic of France, residing at the city of Limoges, in the Department of Hautevienne, France, have invented a new, original, and ornamental Design for a Covered Dish or Similar Article, of which the following is a specification, reference being had to the accompanying drawing, forming part thereof.

Fig. 1 is a side elevation; and
Fig. 2 is a top plan view of a covered dish, showing my new design.

I claim:

The ornamental design for a covered dish or similar article as shown.

Signed at the city of Limoges, Department of Hautevienne, France, this 26th day of February, 1926.

LUCIEN ANDUZE.
